UNITED STATES PATENT OFFICE

163,629

LINE WINDER

Joseph A. Perko, Cleveland, Ohio

Application May 24, 1949, Serial No. 2,857

Term of patent 7 years

(Cl. D49—1)

To all whom it may concern:

Be it known that I, Joseph A. Perko, a citizen of the United States, residing at 4538 Turney Road, city of Cleveland, county of Cuyahoga, State of Ohio, have invented a certain new, original, and ornamental Design for a Line Winder, of which the following is a specification, reference being had to the accompanying drawings, forming a part thereof, and in which:

Fig. 1 is a side view in elevation of the line winder, showing my design.

Fig. 2 is an elevational view of the line winder taken from the right edge of Figure 1.

Figs. 3, 4 and 5 show cross-sections of the line winder taken on the points indicated in Fig. 1, namely Fig. 3 on A—A, Fig. 4 at B—B and Fig. 5 on C—C.

I claim:

The ornamental design for a line winder, as shown.

JOSEPH A. PERKO.
